(No Model.)

A. H. ELDRIDGE.
CUFF HOLDER.

No. 423,861.

Patented Mar. 18, 1890.

UNITED STATES PATENT OFFICE.

ANDREW H. ELDRIDGE, OF SYRACUSE, NEW YORK, ASSIGNOR OF THREE-FOURTHS TO A. HOLTON MATSON AND JOHN VAETH, OF SAME PLACE.

CUFF-HOLDER.

SPECIFICATION forming part of Letters Patent No. 423,861, dated March 18, 1890.

Application filed July 5, 1889. Serial No. 316,640. (No model.)

To all whom it may concern:

Be it known that I, ANDREW H. ELDRIDGE, of Syracuse, county of Onondaga, in the State of New York, a citizen of the United States, 5 have invented certain new and useful Improvements in Cuff-Holders, of which the following is a specification, reference being had to the accompanying drawings, in which—

Figure 1 is a side elevation of my improved 10 cuff-holder; Fig. 2, a top plan view; Fig. 3, a bottom plan view; and Fig. 4, a longitudinal section of the cuff-holder, and illustrating its attachment to the interior of a coat-sleeve and a cuff.

15 Similar letters and figures of reference indicate corresponding parts throughout the several views.

My invention relates, broadly, to that class 20 of devices designed for holding cuffs in proper position by adjustably connecting them within or to the sleeve of a coat or other garment.

My object is to produce a cuff holder or fastener of improved construction, great durability, easy of manipulation, comparatively 25 inexpensive of manufacture, and particularly adapted from its formation to be secured to the lining in a coat-sleeve or the seam protuberance back thereof, although correspondingly applicable for attachment to the exterior 30 of a garment-sleeve as well.

It consists in the several novel features of construction and operation hereinafter described, and which are specifically enumerated in the claims hereunto annexed.

35 It is constructed as follows:

A is an elongated metallic plate comprising a body portion 1, provided at its forward end with a short vertical cuff-engaging hook *a*, standing upwardly, and at its opposite or rear 40 end having a safety fastening-pin *b*, provided with a guard *c*, said pin and guard being secured (at a downward inclination) in an eye *d*, formed by bending the rear extremity of the body 1 over upon itself, and *e e* are side 45 pieces bent up vertically to the body, and *f* is a pivot-pin transversely inserted through the said side pieces.

B is an elongated pivoted plate comprising a body portion 2 and mounted upon the pivot-pin *f* by perforated ears *g g*, fitting over the

aforesaid pivot-pin, said pivoted plate lying longitudinally above the body 1 of the plate A, as shown, and formed of a metallic strip. At the rear end of the pivoted plate B (which but slightly projects beyond its point of pivot) I form a semicircular projection *h*, (adapted for the pressure thereon of a person's finger) that is stamped up from the metal body. At the forward extremity of the said plate B, in proximity to the cuff-engaging hook *a*, are downward side projections *i i*, and rearwardly therefrom and centrally of the body is stamped out and up the auxiliary securing-pin *K*, rising slightly angularly from the plate body, and thence extending 60 horizontally the desired distance forward, its pointed extremity facing the vertical cuff-hook *a* of the plate A. Around the pivot-pin *f*, I place a coiled spring *l*, disposed in such manner as to hold normally the forward downward projections *i i* of the pivoted plate B against the fabric that may be interposed between their bottom edges and the adjacent body portion 1 of the plate A.

m m' are longitudinally-disposed corrugations or projections created in the body portion of the plates A B, respectively, by proper stamping, thereby serving to re-enforce and stiffen said plates both longitudinally and transversely, insuring them increased strength and 75 durability, and is particularly advantageous when the aforesaid plates are formed of very thin metal, which, being of lighter weight and less expensive than the thicker metal ordinarily employed, it is advantageous to utilize, provided sufficient staying qualities may be imparted to the parts formed thereof, and can be by my manner of re-enforcing by central longitudinal corrugations.

As will be readily observed, the lower plate 90 A, comprising the body portion 1, cuff-hook *a*, eye portion *d*, side pieces *e e*, and corrugation *m*, is formed of an integral blank properly bent to shape; also, that the pivoted upper plate B, comprising its body portion 2, 95 perforated ears *g g*, semicircular projection *h*, forward downward projections *i i*, auxiliary securing-pin *K*, and corrugation *m'*, is formed of an integral blank properly bent to shape, all a matter of value in the lessening of the 100

cost of and time in the manufacturing of my cuff-holders.

To secure my device to a garment-sleeve and a cuff, I proceed substantially as follows:

5 Taking, for example, a coat-sleeve, I grasp the cuff-holder, and, placing the rear extremity thereof up the interior of the sleeve a desired distance, I forwardly thrust the auxiliary pin K longitudinally into the sleeve lining or 10 seam, thus securing it in place. Then, having secured that, I next insert the safety fastening-pin b transversely into the lining or seam and securing it in its guard portion. Next, taking the cuff, I insert the cuff-engaging 15 hook a of the plate A into the rear or inner button hole or holes of said cuff, but previously raising the pivoted plate B, and then, upon the insertion of the cuff end and the passing of the cuff-engaging hook a through 20 the button hole or holes, release the pressure of my finger and permitting the downward forward projections i i of the pivoted plate B to close upon and grip the interposed cuff end.

To separate the parts, the action of the 25 holder is reversed.

My employment of the auxiliary securing-pin K is of material advantage, as its use prevents all lateral movement or swaying of the cuff within the coat-sleeve, and also retains it 30 in close longitudinal contact therewith, and thus remedying features so objectionable in ordinary cuff-fasteners.

Having thus fully described my invention, what I claim as new, and desire to secure by 35 Letters Patent, is—

1. In a cuff-holder, in combination, an elongated metallic plate provided with a cuff-engaging hook at its forward end, a fastening-

pin at its opposite end, intermediate side pieces having a transverse pivot-pin connected thereto and on which is pivoted a spring-actuated upper plate constructed with a finger projection at its rear end, a cuff-impinging projection at its forward end, and an intermediate securing-pin rising from the plate-body, substantially as described. 40 45

2. A cuff-holder consisting of an elongated lower plate, comprising a body portion provided with a vertical engaging-hook at its forward end, a transversely-mounted safety fastening-pin at its opposite rear end, intermediate side pieces having a pivot-pin transversely inserted through them, and a central longitudinal corrugation in the plate-body, an elongated upper plate pivotally secured by 50 55 perforated side ears upon the pivot-pin and lying above the lower plate longitudinally therewith and comprising a body portion terminating with a finger projection at its rear end, downward side projections at its forward end adjacent to the vertical engaging-hook of the lower plate, an intermediate horizontal securing-pin rising from the upper plate-body longitudinally therewith and its pointed end extending forwardly, a central longitudinal 60 65 corrugation in the plate-body, and a coil-spring upon the pivot-pin adapted to bear against the upper and lower plates, all combined and operating together substantially as described, and for the purposes specified. 70

In witness whereof I have hereunto set my hand this 20th day of May, 1889.

ANDREW H. ELDRIDGE.

In presence of—

W.M. C. RAYMOND,
FRANK E. WRIGHT.
